VEGETABLE TRIMMER OR THE LIKE

George H. Cooke, 18521 Prairie St., and William J. Carl,
8601 Oak Park Ave., both of Northridge, Calif. 91324

Filed Feb. 9, 1966, Ser. No. 969

Term of patent 14 years

(Cl. D89—1)

FIG. 1

We claim:

The ornamental design for a vegetable trimmer or the like, substantially as shown.
